UNITED STATES PATENT OFFICE.

ROBERT H. GILFILLAN, OF NEW HOLLAND, PENNSYLVANIA, ASSIGNOR TO STORE, SNADER & COMPANY, OF NEW HOLLAND, PENNSYLVANIA, A CORPORATION OF PENNSYLVANIA.

LET-OFF MECHANISM FOR LOOMS.

Application filed August 18, 1921. Serial No. 493,291.

To all whom it may concern:

Be it known that I, ROBERT H. GILFILLAN, a citizen of the United States, residing at New Holland, in the county of Lancaster and State of Pennsylvania, have invented certain new and useful Improvements in Let-Off Mechanism for Looms; and I do hereby declare the following to be a full, clear, and exact description of the invention, 10 such as will enable others skilled in the art to which it appertains to make and use the same.

This invention relates to tension devices for use in yarn supplying mechanisms for power looms and more particularly to mechanism for letting off and taking up the warp so as to maintain the proper tension thereon during the operation of weaving.

The common method of tensioning the warp threads of looms is by means of friction devices, such for example as a strap wound around the warp beam and having weights suspended from its lower end. When for any reason an adjustment is 25 necessary the operator is compelled to go behind the loom and lift the weight and this is extremely objectionable as the operators are often girls, who are unable to stand up under the strain of this back breaking task.

One object of the invention is to overcome the objections above noted and to provide a device of the character referred to consisting of few parts and with pawl and ratchet mechanism capable of letting-off the 35 thread an almost infinitesimal amount or as much as is desired, and better and more generally applicable for various grades and sizes of material.

A further object of the invention is to 40 obviate the necessity for going to the rear of the loom and lifting the weight when making an adjustment, by providing means operable from the front of the loom whereby the let-off motion may be thrown out of 45 gear and the tension on the warp released to enable the operator to pick out imperfections or make necessary adjustments.

The invention will first be hereinafter 50 more particularly described, with reference to the accompanying drawings, which are to be taken as a part of this specification, and then pointed out in the claims at the end of the description.

In said drawings,

Fig. 1 is a side elevation, partly broken

away, of a loom showing my improvements applied thereto;

Fig. 2 is a rear view partly in section, showing the warp beam, whip roll and associated parts embodying my invention; 60

Fig. 3 is a top plan view of my invention; Fig. 4 is a detail fragmentary side view of the let-off mechanism; and

Fig. 5 is a detail view at right angles to Fig. 4. 65

Referring to said drawings in which the same reference numerals are used to denote corresponding parts in different views, the numeral 1 designates generally the frame of a loom as ordinarily constructed provided with the usual lay and operating mechanism which it is unnecessary to describe, and having the usual main driving shaft 2 journaled in suitable bearings at a point slightly rearwardly of the middle of the frame. Parallel to shaft 2 and at a point near the rear of the machine is mounted a warp beam shaft 3, carrying a warp beam 35. A whip-roll 4 is mounted adjacent the rear end of the frame 1 on the arms 5 of a pair of bell crank levers pivoted at 6 and having arms extending toward the front end of the loom. Suspended by a cord or other suitable means from each of the forward extensions 7 of the arms 5 are weight-members W consisting of one or more weights, which serve to maintain tension on the yarn as it is unwound from the warp beam 35 and passes around the whip-roll 4 which is revolvably mounted on the arms 5. On one side of the machine, attached to the end of one of the arms 5 and movable therewith is a depending rod or bar 8 having adjustably connected thereto at its lower end one end of a horizontal bar 10, by means of an oblong slot 9 in the bar 10, and a pin or screw 8^a protruding from the bar 8 through said slot. An adjusting screw or bolt 11 is also carried in one end of the slot 9, and may be moved to shorten the reciprocatory motion of the pin 8^a in the slot 9. In the opposite end of arm 10 is a pin 12, which is adapted to move in an arcuate slot 13 in a lever 14, which is pivoted at one end, as at 15, to a bracket 16 adjustably attached to the loom frame 1 by means of a bolt or screw entering a vertical slot in the bracket 16. Movement is imparted to the operating lever 14 by means of a cam 17 on the main shaft 2, in contact with an extension 14^a of the lever 14. The 85

pin 12 also passes through a link 18, which is connected by means of another link 19 to the short arm of a bell crank lever 20, the long arm 21 of which carries a plurality of actuating pawls 22, adapted for engagement with a ratchet wheel 29 mounted upon a horizontal shaft 30, extending lengthwise of the loom. The pawls 22 are preferably constructed of different lengths in order that the ratchet wheel may be moved as much as one notch or tooth or as little as one-third of one notch. Thus it will be seen that the let-off motion is extremely delicate in its operation. The horizontal shaft 30 is provided at the front with a hand wheel 31 and at the rear with a worm 32 which intermeshes with a gear 33 on the warp beam shaft 3. A rod 23 having a cut-away portion or recess 24 therein projects through a socket 25 attached to or integral with the bell crank lever 21, and is connected, by means of a link 26, to a lever 27, which is pivoted at 28 at or near the front of the loom frame 1.

In the process of weaving, after each throw of the shuttle the lay L beats up, and the cloth beam, (not shown) is operated to take up the woven fabric. The tension thus exerted causes the arms 5—7 to move about the pivots 6 and slightly raise the weight W. This movement is transmitted through lever 8 to arm 10, which actuates the pin 12 so as to vary its position in the slot 13, and the operating lever 14, being oscillated or raised by the rotation of the shaft 2 so as to cause the cam 17 thereon to engage said lever, imparts a reciprocatory movement to the links 18 and 19 and rocks bell crank lever 20 to actuate the pawls 22. This lever 20 will be given a longer or shorter stroke depending upon the position of the pin 12 in the slot 13 so that the pawls engaging the teeth of the ratchet wheel 29 on the shaft 30 will rotate the same intermittently step by step, and impart a corresponding step by step movement to the warp beam 35, so that the warp will be automatically let-off as needed. The let-off therefore depends upon, and its adjustment is automatically governed by the tension of the threads between the cloth beam and the warp beam.

In the operation of the loom the yarn is unwound from the warp beam, passes over the whip-roll, through the heddles and reed and finally is wound around the cloth beam. The whip-roll vibrates in response to the movement of the shedding mechanism, that is, each time the shedding mechanism opens the whip-roll is pulled slightly forward and is allowed to move rearwardly under the tension of the weights as the shedding mechanism closes. A constant tension is therefore maintained on the warp and the let-off mechanism supplies the proper amount of yarn for the weaving operation.

In normal operative position the pawls 22 are opposite the recess or cut-away portion 24 in the rod 23. Should it be necessary to pick out a defective thread, the operator will grasp the hand lever 27 and move it so as to cause that portion of the rod 23 forward of the cut-away portion 24 to engage the pawls 22 and withdraw them from engagement with the ratchet wheel 29. The operator may then by turning hand wheel 31 rotate shaft 30 and let back on the warp beam, by means of the worm 32 and gear 33.

From the foregoing description it will be readily understood that my invention provides let-off mechanism which is simple in construction and efficient in operation, the warp threads being automatically and properly fed under the proper tension at all times during the weaving operation without the use of frictional devices or the like, for tensioning the warp. The tensioning devices are also capable of adjustment so that yarns of various grades and sizes are readily usable in a loom equipped with my improved let-off mechanism.

The motion in my improved let-off mechanism is positive in action letting off the exact amount each time and does not place any extra tension on the warp at anytime. No frictional devices are employed to operate my let-off motion as the warp is tensioned by weights to the required amount for each particular quality or grade of goods being woven and remains the same throughout the entire length of the warp.

Having thus described my invention, what I claim as new and desire to secure by Letters-Patent is:

1. In a loom, a warp beam, a shaft extending lengthwise of the loom geared to the warp beam, a handwheel on said shaft at the front of the loom, a ratchet on the shaft between the handwheel and the warp beam for letting off, a lever pivoted on the shaft, pawls on the lever engaging the ratchet, a cam slidably mounted on said lever and adapted to render said pawls inoperative, and a hand lever at the front of the loom connected to said cam, substantially as set forth.

2. In a loom, a warp beam, a shaft extending lengthwise of the loom geared to the warp beam, a handwheel on said shaft at the front of the loom, a shaft extending across the loom, connections between said shafts for normally driving the warp beam in a direction to let off the warp, and means operable from the front of the loom for disabling said driving connections whereby the warp-beam may be turned back by means of said handwheel, substantially as set forth.

3. In a loom, a warp beam, a whip-roll, a shaft geared to the warp beam, means for driving the shaft with a variable stroke including a lever, means for operating the

- ratchet on the shaft, a pawl therefor, a lever with a constant stroke, a link movably connected to the lever for operating the pawl with a variable stroke, and means controlled 5 by the movement of the whip-roll for determining the relation of the link to the lever, substantially as set forth.
4. In a loom, a warp beam, a whip-roll, a shaft geared to the warp beam, means for 10 driving the shaft with a variable stroke including a lever, means for operating the lever with a constant stroke, said lever having a longitudinal slot, a link operated by the lever, said link having a projection mov- 15 able in the slot to vary the stroke of the link, connections from the link to said shaft for operating the same, an arm swinging with the whip-roll, and an adjustable lost motion connection between said arm and the pro- 20 jection on said link, substantially as set forth.
5. In a loom, a warp beam, a whip-roll, a shaft extending lengthwise of the loom geared to the warp beam, a handwheel on
- 25 said shaft at the front of the loom, a ratchet on the shaft between the handwheel and the warp beam for letting off, a lever pivoted on the shaft, pawls on the lever engaging the ratchet, a cam slidably mounted on said lever adapted to render said pawls inop- 30 erative, a hand lever at the front of the loom connected to said cam, an oscillatory lever beneath said ratchet having a longitudinal slot, a link attached to the pawl lever and having a projection engaging the slot, an 35 arm swinging with the whip-roll, and a link attached to said projection and adjustably connected to said swinging arm for varying the point of connection of said link and said oscillatory lever to vary the action of the 40 pawl and ratchet mechanism, substantially as set forth.

In testimony whereof I affix my signature in the presence of two witnesses.

ROBERT H. GILFILLAN.
